Des. 234,652
Patented Apr. 1, 1975

234,652

INVERTIBLE CHAIR FOR AN INFANT

Earl R. Schug, San Bruno, Calif.
(135 S. La Salle St., Suite 1123, Chicago, Ill. 60603)

Filed Jan. 24, 1973, Ser. No. 326,469

Term of patent 14 years

Int. Cl. D6—01

U.S. Cl. D6—3

770-1

770-2

770-3

770-4

770-5

FIG. 1 is a side elevation of an invertible chair for an infant embodying my new design;

FIG. 2 is a front elevational view of the chair;

FIG. 3 is a top plan view of the chair;

FIG. 4 is a rear elevational view of the chair; and

FIG. 5 is a side elevational view of the chair illustrating another position in which it may be used.

I claim:

The ornamental design for an invertible chair for an infant, substantially as shown.
